UNITED STATES PATENT OFFICE.

HERMAN G. BLOSSER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 8, 1924, Serial No. 684,961. Renewed January 23, 1926.

To all whom it may concern:

Be it known that I, HERMAN G. BLOSSER, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising loop circuits or local circuits for the control of train carried governing means.

I will describe one form of trackway apparatus embodying my invention, and will then point out the novel features thereof in claims.

The accompanying drawing is a diagrammatic view showing one form of trackway apparatus embodying my invention.

Referring to this drawing, the reference characters 1 and 1^a designate the track rails of an electric railway. Propulsion current is supplied to these rails through an impedance 5 and to a trolley or third rail 6, from a suitable source of energy such as a generator E. As here shown, the propulsion current is an alternating current. The track rails 1 and 1^a are divided, by means of insulated joints 2, into a plurality of successive sections A—B, B—C, C—D, etc. Propulsion current is conducted past each pair of insulated joints by an impedance bond H. Referring particularly to the impedance bond H at point B, this bond comprises two impedances 3 and 3^a, connected across the rails adjacent the right-hand end of section A—B and across the rails adjacent the left-hand end of section B—C, respectively.

The mid points of these impedances 3 are connected together by a conductor 4 in the usual manner.

Each track circuit is provided with a "loop" circuit which is supplied with alternating loop current from a loop transformer designated by the reference character T with an exponent corresponding to the location. Primary 8 of each loop transformer T is constantly supplied with alternating current from an alternator G, over line wires 7 and 7^a. Referring particularly to section A—B, the loop circuit for this section passes from secondary 10 of transformer T^B, through wire 13, winding 11 of an inductive im-

pedance J^B, wires 20 and 4, and impedance 3 at point B to the rails of section A—B, thence through the rails of section A—B to impedance 3^a at point A, wires 4, 14 and 16, impedance 17 and wire 18 back to secondary 10 of transformer T^B.

The loop circuit for section B—C may be traced from secondary 9 of transformer T^B, through wire 19, winding 12 of inductive impedance J^B, wires 20 and 4, impedance 3^a at point B, the rails of section B—C, impedance 3 at point C, wires 4, 15 and 21, impedance 22 and wire 23 back to secondary 9 of transformer T^B. One purpose of impedances 17 and 22 is to adjust the currents through the respective circuits to the proper value.

The loop currents may be utilized to control traffic in any desired manner.

Under certain conditions a voltage drop is established between the two ends of a section due to the flow of propulsion current in the rails of the section. It is desirable to prevent the flow of propulsion current in the loop circuits to prevent burning out impedances 17 and 22 and the windings of the loop transformers. It is also desirable to prevent the propulsion current from feeding back into line wires 7 and 7^a. It should be noted that in apparatus embodying my invention the propulsion current voltage drop is not effective to send a heavy current through the loop circuit due to the manner of connecting the inductive impedances J. Referring again to the apparatus located adjacent point B, it will be seen that loop current from secondary 10 of transformer T^B flows through winding 11 of impedance J^B in one direction, and loop current from winding 9 of transformer T^B flows through winding 12 of impedance J^B in the other direction. That is, the loop currents in the two portions of impedance J^B are of opposite relative polarity, so that the opposition offered to the flow of these currents by impedance J^B is very small. On the other hand, propulsion current tends to flow through both portions of this impedance in the same direction at any instant. For example when propulsion current tends to flow from point C from right to left through winding 12 of impedance J^B to point B, propulsion current also tends to flow from point B from right to left through winding 11 of

impedance J^B to point A. It will be clear that these two currents oppose each other and as a result the opposition offered to the flow of such currents by impedance J^B is 5 comparatively large and the propulsion current flowing in the loop circuits is limited to a small value.

Although I have herein shown and described only one form and arrangement of 10 trackway apparatus embodying my invention, it is understood that various changes and modifications may be made therein within the scope of the appended claims without departing from the spirit and scope 15 of my invention.

Having thus described my invention, what I claim is:

1. Railway traffic controlling apparatus comprising a stretch of track divided into 20 a forward and a rear track section, an impedance having two portions, a loop circuit for said forward section including one portion of said impedance, and a loop circuit for the rear section including the other portion 25 of the impedance.

2. In combination, two adjoining sections of railway track, an impedance having its mid point connected with the adjacent ends of said sections, means for applying an alternating electromotive force from one terminal of said impedance to the free end of one section, and means for supplying an alternating electromotive force opposite to the 30 instantaneous relative polarity of said first 35 electromotive force from the remaining end of said impedance to the free end of the second said track section.

3. In combination, a forward and a rear track section, an impedance comprising two 40 portions, means for supplying loop current of one relative polarity to said forward section and to one portion of said impedance, and means for supplying loop current of the

other relative polarity to said rear section and to the remaining portion of said impedance. 45

4. In combination, a forward and a rear track section, an impedance bond for conducting propulsion current from one said section to the other, an impedance having 50 its mid point connected with said impedance bond, two sources of alternating current, and means for connecting one said source from the free end of one section to one terminal of said impedance and for connecting the other said source from the free end of the remaining section to the remaining terminal of said impedance. 55

5. Railway traffic controlling apparatus comprising a forward and a rear stretch 60 of railway track, an impedance having its mid point connected with the rear end of said forward section and with the forward end of said rear section, a loop transformer having two secondaries, means for connecting the left-hand end of one said secondary with one terminal of said impedance and for connecting the right-hand end of said secondary with the forward end of said forward section, and means for connecting the 65 left-hand end of the remaining secondary with the remaining terminal of said impedance and for connecting the right-hand end of said remaining secondary with the rear end of said rear section. 75

6. In combination, a plurality of successive sections of railway track, an impedance for each two track sections located adjacent the juncture of such sections, and means for supplying alternating current to each section and a portion of the associated impedance, the current so supplied to the two portions of each impedance being of opposite 80 instantaneous polarities.

In testimony whereof I affix my signature.
HERMAN G. BLOSSER.
